UNITED STATES PATENT OFFICE.

WILLIAM J. FOGARTY, OF ST. LOUIS, MISSOURI, ASSIGNOR TO GEORGE W. DRISCHEL, OF CAMBRIDGE CITY, INDIANA.

DIRECT-ACTING STEAM SHEARING-MACHINE.

SPECIFICATION forming part of Letters Patent No. 738,787, dated September 15, 1903.

Application filed April 7, 1903. Serial No. 151,545. (No model.)

To all whom it may concern:

Be it known that I, WILLIAM J. FOGARTY, a citizen of the United States, residing at St. Louis, in the State of Missouri, have invented 5 new and useful Improvements in Direct-Acting Steam Shearing-Machines, of which the following is a specification.

My invention relates to certain new and useful improvements in direct-acting steam-shears, and throughout this specification and claims wherever I use the term "steam" I wish it understood that such term includes any expansive fluid, although this invention especially applies to steam-actuated means.

15 The objects of my invention are, first, to arrange the mechanism situated between and connecting the piston-rod of the main or knife-head-operating steam-cylinder and the knife-head so that the force applied to said 20 piston-rod and transmitted through said connecting mechanism to the knife-head will be equalized or evenly distributed throughout the entire length of the knife of said knife-head; second, to construct such connecting 25 mechanism so that the stresses due to the resistance against which the said knife-head operates when the knife of the latter is cutting or shearing the material will be transmitted to the said piston-rod in approximately 30 the direction of a vertical line parallel with and centrally on each side of the vertical axis of said cylinder, and, third, to provide a means for cushioning the steam at the ends 35 of the strokes of the pistons of both the main and the holddown cylinders, but particularly the main cylinder, in which when the piston thereof has reached the end of its stroke it is caused to positively stop at such point, thereby 40 positively bringing the said knife-head to a state of rest when the knife thereof has completed its cut and preventing said knife-head overrunning its normal stroke when suddenly released of its load, thereby preventing 45 said knife-head knocking or striking the ends of its guides at each end of its stroke and preventing breakage. I attain these objects by means of the mechanism of the direct-acting steam shearing-machine illustrated in the accompanying drawings, in which similar nu-

merals of reference designate like parts 50 throughout the several views.

Figure 1 is a front elevational view of my invention of a steam shearing-machine. Fig. 2 is a transverse sectional elevational view of the same taken through the line A B. (See Fig. 1.) 55 Fig. 3 is a similar view taken through the line C D. (See also Fig. 1.) Fig. 4 is a sectional elevational view of the main and the holddown steam-cylinders and their controlling-valve and taken through the line E F. 60 (See Figs. 5 and 6.) Fig. 5 is an inverted plan view of said cylinders and looking in the direction of the arrow a. (See Fig. 4.) Fig. 6 is a plan view of said cylinders. Fig. 7 is an elevational view of the lever system of the 65 knife-head. Fig. 8 is a plan view of the same. Fig. 9 is an elevational view of the lever system of the holddown; and Fig. 10 is a plan view of the machine with the steam-cylinder, 70 knife-head, and its connecting mechanism and the holddown removed to more clearly show the lever system of said holddown and the treadle-lever mechanism whereby the valve for controlling said main and holddown cylinders is operated. 75

The end frames or housings 1 and 2, the cylinder-supporting beam 3, which has its ends resting on the top ends of the housings 1 and 2, whereto said beam is securely bolted, and the table 4, which is securely bolted at 80 its ends to said housings 1 and 2, constitute the main frame of the machine.

A knife-head 5 has its ends adapted to accurately fit and to slide or reciprocate vertically in suitable guideways 6, formed in the 85 housings 1 and 2. To the bottom front portion of said knife-head 5 is fitted and securely bolted the top shearing-knife 7, the bottom or cutting edge of which is horizontally inclined relatively to the top or cutting edge of 90 the bottom knife 8. The bottom knife 8 is bolted to the face of the table 4 and adjusted vertically or relatively to the top knife 7 and is preferably adjusted in position, so that the top or cutting edge of said knife will be flush 95 with the top surface of the table 4, by the set-screws 9, which are screwed into the lugs 10, formed integral on the rib 11 of said table 4.

A holding-down head or hold-down 12 is situated in front of the knife-head 5 and is adapted to accurately fit at its ends and to slide in its guides 13, secured on the front faces of 5 the housings 1 and 2.

A main cylinder 14 is securely bolted to the top side of the beam 3 intermediate the ends thereof, and said cylinder is preferably situated centrally over the knife-head 5, and the 10 different parts or elements of the same, which constitute the main feature of this invention, I will hereinafter particularly describe. The piston 15 of said cylinder may be of any suitable or approved type, and said piston is provided with a piston-rod 16, which extends vertically through the divided stuffing-box 17, one, the top portion, formed integral with the cylinder-head 18, and the other, the bottom portion, formed integral with the valve-seat head 20, and on the top end of said piston-rod 16 is firmly secured the cross-head or cross-beam 20, the ends of which are turned to fit the bores of the top ends of the inner and the outer connecting-rods 21 and 22.

25 The knife-head-lever system consists of the shorter lever-arms 23 and 24, which are situated centrally and are keyed or formed integral on their fulcrum-shafts 25 and 26, and said arms have their free ends connected to 30 the lugs 27 and 28, formed integral on the ends of said knife-head 5, by the depending or vertically-extending connecting-links 29 and 30 and the link-pins 31 and 32, which accurately fit the bores formed in the ends of 35 said links, said lever-arms and the lugs to which the latter are connected, and the bores of the levers 23 and 24. The power-levers 33 and 34 are arranged in pairs, one on each side of the main cylinder 14, and all are similar in form and of equal lengths, and said pairs of levers are arranged to be operated simultaneously. The pair of outer levers 33 are keyed or otherwise secured on the outer ends of the fulcrum-shaft 25 exterior of the 40 fulcrum shaft-bearings 35 and have their free bifurcated ends 36 directed inwardly or toward the center of the machine and in position to receive the lower bottom ends of the connecting-rods 21, and similarly the inner 45 levers 34 are keyed on the ends of the fulcrum-shaft 26 exterior of the fulcrum-shaft bearing 37, and said levers have their free bifurcated ends 38 directed inwardly and in position on each side of the main cylinder 50 14 to receive the lower or bottom ends of the connecting-rods 22, and thus the said pairs of levers 33 and 34 are connected to the cross-head 20 to be operated simultaneously to cause an equal and regular movement 55 and an equal distribution of power to be imparted to said knife-head 5 at all points throughout its length. The fulcrum-bearings 35 and 37 are arranged in pairs, one on each side of the lever-arms 23 and 24, and 60 said bearings are situated on the top side of the beam 3 in their proper positions at or

near the ends thereof, whereto they are securely bolted. It will be particularly noted (see Figs. 7 and 8) that the fulcrum-shaft bearings 35 and 37 are so situated on the ends 70 of the beam 3 and the levers 33 and 34 are of such a length that when swung their full extent both ways above and below their horizontal positions the centers of the pins 39 describe equal arcs that intersect at points directly and equally distant above and below the horizontal line passing through their fulcrum-shaft centers, so that the vertical line connecting said points of intersection on each side of the main cylinder 14 will be in the 80 plane that would pass through the center of said cylinder, and thus showing that the forces transmitted from the main-cylinder piston 15, through its piston-rod 16 and cross-beam 20 to the ends of said levers 33 and 34, are 85 equally divided and the line of direction of the same or the resultant forces of all the forces applied directly to the ends of the said knife-head levers 33 and 34 will fall in said vertical lines parallel with and centrally situated on each side of the said main cylinder 14, thereby tending to maintain the piston-rod 16 in vertical alinement and obviating the necessity of providing guideways to preserve the vertical alinement of said piston- 90 rod throughout its travel.

95 The hold-down-lever system consists of the lever 40, having the shorter arm 41, and said lever is securely keyed or otherwise secured on its fulcrum-shaft 42, which latter is adapted to turn in its bearings 43, formed integral with the beam 3, and the lever-arm 44, having the shorter arm 45, is adapted to swing on its fulcrum-pin 46, supported by the bearings 47, also formed integral with the beam 100 3, and the said lever-arms 40 and 44 are equal in length and have their power or free ends directed inwardly or toward the center of the machine and are situated in the same vertical plane, the one above the other, and are 105 connected at said free ends by the connecting-link 48, so as to be operated simultaneously. The shorter arms 41 and 45 of the levers 40 and 44 are connected to the hold-down 12 by the adjustable connecting-links 49, which are 110 hinged at their top and bottom ends on their link-pins 50. The main lever 51 of the hold-down system is keyed on the fulcrum-shaft 42 and has its power end connected to the piston-rod 52 of the hold-down-cylinder 53 by the 115 connecting-links 54.

120 I will now proceed to describe the peculiar construction and function of the main cylinder 14 and the hold-down-cylinder 53 and the valve for controlling these cylinders, which 125 mechanism constitutes the main feature of my invention.

130 The main cylinder 14 is situated centrally and disposed vertically on the center of the supporting-beam 3, the web 56 of which forms the cover for the bottom open end of said cylinder and to which beam said cylin-

der is securely bolted by suitable bolts or studs 57, which pass through said web 56 and are screwed into the inner flange 58. The cushion valve-plate 59 is truly faced and turned to accurately fit the bore of said main cylinder 14 and to fit and to seat on the top-faced surface of the cylinder-flange 58 and form a steam-tight joint therewith, and the said cushion valve-plate 59 is provided with a suitable number of valve-openings to obtain the necessary steam-inlet area, and in said valve-openings are fitted and seated the cushioning and inlet lift-valves 60, which are adapted to raise or move upwardly from their seats to open for admission only of live steam into the bottom end of said main cylinder 14. A guard-ring 59^a is turned truly to fit the bore of the main cylinder and may be truly faced on both its top and bottom sides to form true surfaces, the bottom surface of which rests or is seated on the top trued surface of the valve-plate 59, and the top surface of said ring is adapted to contact with the piston 15 to prevent said piston contacting with or striking the lower inlet and cushioning valves 60 and also forming a seat upon which said piston may rest when the machine is not in operation. The upper head of said main cylinder, previously described, is composed of two parts, one the outer head 18 and the other the inner head 19. The inner head 19 has its cylindrical portion 61 turned truly to accurately fit the bore at the top end of said main cylinder 14, and a Z-formed separating-partition 62, formed integral with said head, divides the recess or chamber formed in said cylindrical portion 61 of said inner head 19 into two separate chambers 63 and 64, one of which, the chamber 63, is provided with the inlet-port or steamway 65, and the other, the chamber 64, with the inlet-opening 66, which connects said chamber 64, and the horizontally-extending or valve-seat portion of said partition 62 is bored to form valve-ways in which the cushioning and inlet valves 67 are fitted and seated and adapted to lift or move upwardly to open for admission only of steam into the top end of said main cylinder. The inner head 19 is faced on its bottom bearing-surface to accurately fit the top surfaced end of said main cylinder 14 to form a steam-tight joint therewith, and the under bearing-surface of the outer head 18 is faced to be fitted to the faced or trued top surface of the inner cover 19 to form a steam-tight joint therewith, and both of said heads are securely bolted to the top end of said cylinder 14 by suitable bolts 68, which pass through said covers 18 and 19 and are screwed into the end of said main cylinder. The main cylinder 14 is provided with the main steam ports or passages 69 and 70, which extend from the end chambers 63 and 71, respectively, to positions on the steam-chest face 72, best adapted to connect with the main controlling-valve hereinafter set forth.

It will be readily seen and understood on

an examination of Fig. 4 that the extreme possible stroke of the piston 15 is limited to the distance between the inner surface of the inner cover 19 and the top surface of the guard-ring 59^a, and this extent of the stroke of the piston 15 is slightly in excess of the normal stroke or the movement required to be imparted to the knife-head 5. Now in order to limit the stroke of said piston to the extent of the motion to be imparted to said knife-head 5 I provide the end education or cushion ports 73 and 74, which connect each of said ports or steamways 69 and 70, with the ends of said main cylinder on opposite sides of said piston 15 equally distant from the effective ends of said cylinder—that is, equally distant from the inner surface of the top cover 19 and the inner surface of the valve-plate 59—so that, for example, when the piston 15 moves downwardly till it covers the cushion-port 74 the steam is confined in the bottom space of said cylinder between said piston 15 and the valve-plate 59 to form a cushion to absorb the impact of said piston, and thereby prevent any further downward movement of the latter. A similar cushion is formed in a similar manner at the top end of said cylinder, the purpose and object of which I shall hereinafter more particularly refer to.

The main valve-chest or steam-chest 75 is situated intermediate the main cylinder 14 and the holddown-cylinder 53, and the said steam-chest 75 has its main-cylinder face faced to accurately fit the valve or steam-chest face 72 to form a steam-tight joint therewith and to which said steam-chest is securely bolted. The opposite or holddown steam-chest face 76 is also faced to accurately fit the faced steam-chest surface 77 of the holddown-cylinder 53 to form a steam-tight joint therewith and to which latter said steam-chest is securely bolted. The piston 78 of said holddown-cylinder 53 may be of any approved type provided with any suitable form and number of packing-rings 79, and said piston is firmly secured on the reduced end 80 of its piston-rod 52. The top end of said holddown-cylinder 53 is faced, to which end is fitted the head 81, to be secured to said cylinder and to form a steam-tight joint therewith. The lower or bottom head of said holddown-cylinder is composed of two parts, the outer head or cover 82 and the inner head or cover 83. The inner head 83 has its cylindrical raised portion 84 truly turned to accurately fit the bore of said holddown-cylinder 53, and the inner bearing-face of said head 83 is faced to fit the faced bottom-end surface of said holddown-cylinder 53 to form a steam-tight joint therewith, and the outer face of said head is faced to fit the trued bearing-face of said outer head 82 to form a steam-tight joint therewith, and said heads 82 and 83 are securely held together and to the end of said cylinder by suitable securing-bolts 85. The inner end of the cylindrical portion 84 of said cylinder-head 83 is provided with suitable

valve-openings into which the inlet lifting-valves 86 are fitted, and said valves are adapted to open to admit steam only into the lower end of said cylinder 53. Integral with and on the inner surface of the cylindrical portion 84 of said head 83 is formed the guard-ring 86^a, which is provided for the same purpose as the guard-ring 59^a. A stuffing or packing box 87 is formed centrally on and integral with the head 83 and is a continuation of the stuffing-box 88, formed integral with and centrally on the outer head 82, and said stuffing-box is provided with a suitable gland 89. An inlet-port 90 connects the chamber 91 with the steam-inlet port 92.

The holddown-cylinder 53 is provided with the steam-ports 92 and 93, one of which, 92, extends from the chamber 91 to the steam-inlet port 94, formed in the steam-chest face 76, and the other, the port 93, extends from the top end of said cylinder 53 to the steam-port 95. An eduction or cushioning port 96, situated a suitable distance above the bottom head 83, connects the port 92 with the interior of said cylinder 53, and said port is provided for practically the same purpose as the cushioning-ports 73 and 74 of the main cylinder 14.

The valve-chest or steam-chest 75 is bored vertically to receive the valve sleeve or bushing 98, which latter is provided with a series of peripheral bores 99, 100, 101, 102, 103, and 104, the number of which in each of the series of rings depending on the amount of area required, and each of said series are in parallel relation and correspond and connect with their ports 94, 105, 95, 107, 108, and 109, respectively. The open ends of said steam-chest 75 and said sleeve and bushing 98 are closed on their top ends by the cover 110, which is faced to accurately fit the top surface of said steam or valve chest to form a steam-tight joint and to which it is securely bolted, and the bottom open end of said steam-chest and bushing are closed by the bottom cover or head 111, which is similarly faced to fit the faced undersurface of said steam-chest 75 to form a steam-tight joint and to which it is firmly bolted. A packing or stuffing box 112 is formed integral on the lower head 111, and the same is provided with a suitable packing-gland 113. A boss 115 is formed centrally and integral on the top cover 110, and said boss is bored and tapped to receive the steam-supply pipe 116, whereby live steam is supplied to operate the machine. Bosses 117 and 118 (see Figs. 5 and 6) are formed integral on the side of said steam-chest 75 and have their bores connecting with the exhaust-ports 105 and 108, respectively, and to said bosses are connected the exhaust-pipes 119 and 120, (see Figs. 5 and 6,) whereby the exhaust-steam is carried away to a convenient place.

The piston-valve 121 is cylindrical in form and has its ends open, so that the steam admitted into the top end chamber—i. e., the

interior of the sleeve or valve bushing 98—will flow through said valve 121 into the lower bottom end of said chamber, and at the open ends of said piston-valve 121 are formed the spiders 122 and 123, which are bored to receive the reduced end 124 and 125 of the valve-stem 126, and the said stem 126 is secured to said valve by the securing-nut 127. Steam-ports 128 are formed centrally in the cylindrical portion of said valve and are provided for the purpose of supplying steam to either of the admission-ports when said valve 121 is moved in position to admit steam to either steam-inlet ports. The valve-collars 129, 130, 131, and 132 are formed integral on the periphery of said valve 121 and in parallel relation and are so situated in said valve that when the latter is placed in mid-position said collars will cover each of the steam-ports 94, 95, 107, and 109 and prevent further movement of either main or holddown pistons.

The bottom end of the valve-stem 126 is connected to the lever-arm 133 by the connecting-links 134, and the said lever is secured or keyed on its shaft 135, which works or turns in its bearings 136. The lever-arm 137 is secured or keyed to said shaft 135 and has its free end connected to the top end of a connecting-rod 138, which latter is connected at its bottom end to the free end of the shorter lever-arm 139 of the treadle-lever 140. The treadle-lever 140 is pivoted on its fulcrum-pin 141, secured to the end housing 2 of the machine, and intermediate the fulcrum thereof and the free end of the shorter arm 139 of said treadle-lever is connected to the trip-rod 142, which extends upwardly through and sufficiently far beyond the trip-lug 143 to receive the trip-collar 144. The trip-lug 143 is formed integral on the outer end of the lug 27 of the knife-head 5. The trip-collars 144 and 145 are adjustably secured on said trip-rod 142 and are set in position thereon to automatically move or operate the valve 121 to reverse the movements of the pistons 15 and 78 of the main cylinder 14 and the holddown-cylinder 53 and maintain a continuous movement of the knife-head 5 and the holddown 12 when such is required.

The practice of my invention I will now proceed to describe. The sheet of metal to be sheared or dressed is first placed in position on the table 4, with the portion to be removed or separated from the main sheet overlapping the cutting edge of the bottom knife 8. The operator now opens the valve 121 to admit steam first through the port 99 into the port 94, then through the port 102 to the port 107, thereby causing the pistons 15 and 78 of the said holddown steam-cylinder and the said main steam-cylinder to move downwardly—first, the holddown-piston 78 to cause the holddown to descend to clamp the sheet 130 to be dressed firmly to the supporting-table 4, and next, quickly following thereafter, the piston 15 of the main cylinder 14 to cause the knife-head to also descend to shear the

sheet, which operation is accomplished by one single downward stroke of the knife-head 5, and when the knife 7 of said knife-head 5 has completed its cut or that portion of the 5 knife-edge of said top knife 7 farther remote from the edge of the bottom knife 8 has either approached or slightly lapped over the top cutting edge of the lower knife 8 the piston 15 has reached that position where it closes 10 the cushion-port 73, thereby confining the steam in the top inclosed steam-space of the main steam-cylinder 14 to form a cushion, thereby preventing a further movement of 15 said piston 15 and preventing the latter striking the cover or head of said cylinder at the end of its stroke. Another important and necessary object attained by the said cushioning of the piston 15 will be readily appreciated from the following: Suppose the knife 20 7 is making a heavy cut or cutting sheet metal the width of which extends the entire length of the shearing-knives 7 and 8. Then it is clear that steam must be admitted at full pressure the entire length of the stroke 25 of the main piston 15 to cause the full power of the steam-cylinder 14 to be applied to the knife-head 5 and its shearing-knife 7, connected thereto, to shear the entire width of metal, and when said knife 7 has reached the 30 end of its cut and passed through the metal to be sheared the resistance to said knife will be suddenly and immediately removed, and were there no elastic or yielding cushioning means employed to resist or absorb the impact of said piston and bring the latter to a 35 state of rest said piston would continue to move, due to the expansive force of the steam in the cylinder, and would strike the cylinder cover or heads with great force and with 40 sufficient force to break said cylinder-heads.

The cushioning arrangement in connection with the holddown-cylinder is provided for the purpose of preventing the piston thereof striking the heads of said holddown-cylinder 45 with any degree of force, particularly when on the downward stroke—that is, when the holddown is being raised or elevated to release the sheet that is being operated upon. By the above-described means of cushioning 50 the pistons of said cylinders an easy and noiseless movement of the mechanism is obtained and all danger of breaking any of the moving parts is avoided.

Having thus fully described this my invention, what I claim as new and useful, and desire to cover by Letters Patent of the United States therefor, is—

1. In a direct-acting shearing-machine, the combination with a descending knife-head, a 60 fixed shearing-table, and a steam-cylinder, of knife-head-operating levers arranged in pairs on opposite sides of said steam-cylinder and having their free or power ends overlapping and means whereby said levers are connected 65 to said knife-head and said steam-cylinder.

2. In a direct-acting steam shearing-machine, the combination with a descending

knife-head, a fixed shearing-table, and a steam-cylinder, of knife-head-operating levers arranged in pairs on opposite sides of 70 said steam-cylinder and having their free or power ends overlapping, and means whereby said levers are adjustably connected to said steam-cylinder and said knife-head.

3. In a direct-acting steam shearing-machine, 75 the combination with a descending knife-head, a fixed shearing-table, a steam-cylinder, of knife-head-operating levers arranged in opposing pairs, and having their power ends joined on a common axis on opposite sides of said steam-cylinder, and means whereby said levers are connected to said steam-cylinder and said knife-head to impart motion to the latter.

4. In a direct-acting steam shearing-machine, 80 the combination with a descending knife-head, a fixed shearing-table, a vertically-extending steam-cylinder situated over said knife-head, of knife-head-operating levers arranged in opposing pairs and having their 85 free or power ends joined on opposite sides of said steam-cylinder, and means whereby said levers are connected to said steam-cylinder and said knife-head to impart motion to the latter.

5. In a direct-acting steam shearing-machine, 90 the combination with a descending knife-head, a fixed shearing-table, a steam-cylinder, its piston and piston-rod, of knife-head-operating levers arranged in opposing 95 pairs and having their free ends joined on opposite sides of said steam-cylinder, means connecting said knife-head and levers and means connecting said levers and piston-rod whereby said levers are operated simultaneously and uniform motion is imparted to said 100 knife-head.

6. In a direct-acting steam shearing-machine, 105 the combination with a descending knife-head, a fixed shearing-table, a steam-cylinder, its piston and piston-rod, of knife-head-operating levers arranged in opposing 110 pairs and having their free ends joined on opposite sides of said cylinder, means connecting said levers and said knife-head, and 115 adjustable connecting-rods connecting the free ends of said levers on each side of said steam-cylinder whereby said levers are operated simultaneously.

7. In a direct-acting steam shearing-machine, 120 the combination with a descending knife-head, a fixed shearing-table, a steam-cylinder, its piston, piston-rod, and a cross-beam fixed on said piston-rod, of knife-head-operating levers arranged in opposing pairs 125 and having their shorter arms extending outwardly and their longer arms joined on opposite sides of said steam-cylinder, means connecting said short arms to said knife-head, and adjustable means connecting the 130 ends of said beam to the longer arms of said levers whereby motion is imparted to the latter to operate them simultaneously.

8. In a direct-acting steam shearing-ma-

chine, the combination with a reciprocating knife-head and a fixed shearing-table, of a steam-cylinder, its piston and piston-rod, inlet-valves situated at the ends of said cylinder, a main controlling-valve, a lever for operating the valve, a rod pivoted to the lever, and connected to a manual operating means, adjustable collars on the rod and arranged to be engaged by the knife-head to automatically operate the valve, and means connecting said piston-rod and said knife-head whereby motion is imparted to the latter.

9. In a direct-acting steam shearing-machine, the combination with a descending knife-head and a descending hold-down, of a main steam-cylinder and an independent hold-down steam-cylinder, means for connecting said main steam-cylinder and said knife-head, means for connecting said hold-down steam-cylinder and said hold-down; and a single valve arranged between the cylinders for admitting steam alternately to

both of said cylinders, first to the hold-down-cylinder, and next to the main cylinder.

10. In a direct-acting steam shearing-machine, the combination with a descending knife-head and a descending hold-down, of a double-acting steam-cylinder having a cushioning-chamber at each end and a double-acting steam hold-down-cylinder provided with a cushioning-chamber, means for connecting the knife-head and main cylinder, means for connecting the hold-down and hold-down-cylinder, and a single valve arranged between the cylinders for alternately admitting steam to the cylinders.

In testimony whereof I have hereunto set my hand in the presence of two subscribing witnesses.

WILLIAM J. FOGARTY.

Witnesses:

GEORGE BAKEWELL,
G. A. PENNINGTON.
